[57] CLAIM

The ornamental design for a telephone control module case assembly, as shown and described.

DESCRIPTION

FIG. 1 is a front, top, and left side perspective view of a telephone control module case assembly showing our new design;

FIG. 2 is a left side elevational view, the right side being a mirror image thereof;

FIG. 3 is a front elevational view thereof;

FIG. 4 is a top plan view thereof;

FIG. 5 is a rear elevational view thereof; and,

FIG. 6 is a bottom plan view thereof.
